LIGHTING FIXTURE

Hendrik A. J. de Vos, Wenham, Mass., assignor to Sylvania Electric Products Inc., a corporation of Delaware

Filed Dec. 28, 1966, Ser. No. 5,207

Term of patent 14 years

(Cl. D48—31)

The broken line showing of a support standard in FIGURE 1 is for illustrative purposes only.

I claim:

The ornamental design for a lighting fixture, as shown and described.
